UNITED STATES PATENT OFFICE.

WILLIAM HADDOW, OF OSSINING, NEW YORK.

SOAP-DISPENSING MACHINE.

1,015,620.

Specification of Letters Patent. Patented Jan. 23, 1912.

Application filed March 23, 1908. Serial No. 422,826.

To all whom it may concern:

Be it known that I, WILLIAM HADDOW, a citizen of the United States, and resident of Ossining, in the county of Westchester and State of New York, have invented certain new and useful Improvements in Soap-Dispensing Machines, of which the following is a specification.

This invention relates to machines for dispensing soap or similar articles and particularly to that class of such machines as include a rotary member which acts by cutting, scraping, abrading or the like, to granulate or shred material engaged thereby.

My improvements are particularly useful in devices for dispensing in a finely divided state such material as can be obtained in or conveniently molded into cakes, as soap, chocolate, stove polish and the like.

In the drawing accompanying this specification is illustrated one embodiment of my improvements and which may be the preferred embodiment thereof, together with several detail modifications all within the spirit and scope of my invention. Therein Figure 1 is a sectional side elevation on line 10, 10 of Fig. 2 and looking in the direction of arrow 100. Fig. 2 is a front elevation corresponding with Fig. 1 and with part of the front case broken away to better show the construction. Fig. 3 is a plan view of the rotary cutter and Fig. 4 is a section thereof on line 11, 11 of Fig. 3. Fig. 5 is a development into a straight line of a section, on an enlarged scale, on line 12, 12 of Fig. 3 looking in the direction of arrow 120. Figs. 6 and 7 are plan views of modified forms of the cutter shown in Fig. 3. Fig. 8 is a view showing a modified arrangement of my improvements and Fig. 9 illustrates the preferred arrangement of my device relative to a set bowl when said device is used for dispensing soap in a finely divided state.

As illustrated my improvements comprise a receptacle 2 for holding the cakes of material to be dispensed, a rotatable cutter 4 mounted adjacent said case and having blades or teeth 49 for engagement with the material. Said cutter 4 is preferably mounted in the vertical plane but may deviate materially therefrom so that as the material is granulated and removed from the cake those granulations will fall by gravity free of both the cake and cutter. Said material is

illustrated as in two cakes 3 and 30 so that as the lower cake is cut away new material may be supplied in convenient increments.

Receptacle 2 is preferably mounted in a position receding upwardly from the cutting face of cutter 4 so that the cake of material 3 will be urged by gravity against cutter 4. The angle of the axis of cake 3 relative to the plane of cutter 4 is preferably about 45 degrees but said angle may be varied within operability to nearly 90 degrees in one direction and to nearly parallelism in the other. Said receptacle 2 may be conveniently formed of sheet metal or tubing and the lower end 31 thereof may be pressed up from the same piece as the upper part 2 or may be cast or formed in other convenient manner. An arm 32 reaches downwardly therefrom to any suitable means of support such as table 13 of bowl 14. Receptacle 2 may be provided with a central stem 15 conveniently supported on a bar 16 fixed in the lower part 31 of said receptacle. A sleeve or tube is provided between the cakes of material 3 and 30 and stem 15 to prevent abrasion of the hole in said cakes. However if desired said stem 15 and sleeve may be dispensed with and cakes without holes therein be successfully used in my device, but I prefer to support the cake as illustrated rather than by its periphery. A cap 17 preferably having a socket 18 for the reception and support of the top end of stem 15 is provided. Said cap may latch onto receptacle 2 by any convenient means such as the common bayonet latch, not shown, and if desired may be provided with a lock not shown.

Front plate 6 may be secured to lower part 31 of the receptacle by any suitable means such as screws 21. The conjunction of receptacle part 31 and front plate 6 form a housing for cutter 4 and at 22 converge into a discharge chute for the granulated material. Cutting disk 4 is conveniently mounted on the inner end of spindle 5 rotating in sleeve 50 outstanding from front plate 6. On the outer end of spindle 5 is crank 7 having the usual handle 8. Said crank 7 is held on spindle 5 by means of nut 9. Disk 4 has its central hole 19 in hub 20 threaded whereby it may be screwed onto the correspondingly threaded inner end of spindle 5. Said screw threads are right handed so that when crank 7 is turned in

a clockwise direction to drive disk 4 to perform its work, said disk will not tend to unscrew from spindle 5. When said crank is turned in an anticlockwise direction the friction of the disk against the materials is slight and said disk can readily be screwed onto spindle 5 tightly enough to prevent loosening therefrom when so turned in a reverse direction. Furthermore such reverse movement of cutter 4 in no wise deranges any feature or function of my mechanism, as immediately upon turning said cutter in a clockwise direction the device will operate to cut and dispense the cake of material 3. The axis of said disk 4 is located to the left of the center of the cake of material 3 (Fig. 2) whereby when said cutting disk is turned in a clockwise direction it engages said cake first at its upper side and with a portion of said cutter near the periphery thereof and therefore traveling at greater speed than those portions of said cutter nearer its axis of rotation 5. The slower traveling portions of said cutter engage the cake nearer its axis of rotation 15. Thus the engagement of the cutter with the cake of material 3 not only cuts or scrapes portions therefrom but at the same time causes the cake to turn in a clockwise direction with its sleeve 16 on stem 15. Also as said cutter 4 in revolving has a general downward movement relative to that portion of the cake which it engages said cake is thereby fed downwardly against said cutter by the combined action of the cutter and gravity. When cake 3 is first put into receptacle 2 the periphery of the circular end of the cake engages cutter 4 and the cutter in revolving thereupon cuts away that periphery and eventually forms the end of the cake into conical shape as shown. The line of engagement of the cutter with the cake is then the vertical line of tangency of disk 4 and the conical end of cake 3.

Referring now particularly to cutter 4 (Figs. 3, 4 and 5) I will point out several features thereof. Said cutter is preferably formed of one piece of sheet metal having projecting hubs thereon. Said cutting disk has radial slots 23 punched therein and said slots are preferably bridged at their outer ends so as to obtain rigidity of construction. After punching, blades 40, 40 left standing between slots 23, 23 are bent so as to throw up cutting edges 24 on each side of the disk. I preferably do this bending with a punch and die whereby I also slightly swage said blades 40 so as to form acute angled cutting edges 24, 24 thereon. Said cutting blades 40 decrease in their amount of projection beyond the normal faces respectively of the disk as they near the center of said disk (Fig. 4). Thus it will be seen that the depth of cut in the

cake is governed by the amount of inclination of blade 40 to the general plane of the disk (Fig. 5) and that the cut in the cake decreases in depth as the center of the conical end of said cake is approached by the inwardly decreasing inclination of the cutting blades 40. By this means the greatest amount of material is removed from the cake near the periphery of its conical end where there is the greatest supply and less amounts are removed where there is less supply. The action of the cutter on the cake is therefore proportional to the requirements. Furthermore the more gentle action of the cutter near the center of the cake tends to conserve the integrity of said cake when it is nearly consumed and therefore frail.

In Fig. 6 I have illustrated a modification of cutter 4 wherein slots 23 are of greater size and blades 40 made relatively narrower, said blades being bent however as in Fig. 5. This arrangement shown in Fig. 6 furnishes a cutter that produces a heavier cut than the cutter of Fig. 3. In Fig. 7 is illustrated another modification of cutter 4 wherein teeth 25 are punched up from the plate. The cutters of Figs. 3 and 6 are double-faced reversible cutters and after one side has become dulled in use the cutter may be turned over and its usefulness therefore doubled.

In Fig. 8 I have illustrated my device as applied to the cutting of a non-revolving cake 300. Said cake in this arrangement is set entirely at one side of axis 5 of cutter 4 and said cake may be of rectangular section as shown or round or other shape as desired. Also in this arrangement cake 300 may be located at right angles to cutter 4 and by inclining the forward end of axis 5 downwardly proper feed for the cake may be obtained, also efficient discharge of the granulated material.

I claim:

1. The combination of a receptacle having a stem therein for the support and free rotation thereon of a cake of material, a rotatable cutter for engagement with said cake, said cutter being located to one side relative to the cake to impart a rotary movement to the cake during the cutting of said cake, and means to rotate the cutter.

2. In combination with a receptacle, means for rotatably supporting a cake of material therein, and a rotatable cutter, said receptacle and cutter being so positioned relatively to each other and to the vertical that said cake is urged by gravity to engagement with the face of said cutter on one side only of the axis thereof.

3. In a device of the kind described, a receptacle, a spindle therein, and a rotative cutter at one end of said spindle, the axis of the cutter and the spindle being in non-

intersecting lines whereby a cake of material positioned upon said spindle is rotated by the operation of said cutter thereupon.

4. In a machine for dispensing soap or similar articles, a device adapted to receive and support a cake of soap so as to permit a rotary movement thereof, and a rotative cutter positioned at one end of said device and arranged to engage the cake of soap on one side only of its axis of rotation.

5. In a machine for dispensing soap or similar articles, a device adapted to receive and support a cake of soap so as to permit a rotary movement thereof, and a rotative cutter positioned at one end of said device and having its cutting face at an angle with the axis of rotation of the cake of soap positioned in said device and arranged to engage the cake of soap on one side only of its axis of rotation.

6. In a machine for dispensing soap or similar articles, a device adapted to receive and support a cake of soap in an inclined position so as to permit a rotary movement thereof, and a rotative cutter positioned at one end of said device with its axis at an angle with the axis of rotation of the cake of soap positioned therein and arranged to engage the cake of soap on one side only of its axis of rotation whereby said cake is simultaneously fed to said cutter and revolved.

7. In a machine for dispensing soap or similar articles, a cylindrical receptacle adapted to receive and support a cylindrical cake of soap so as to permit a rotary movement thereof, and a rotative cutter positioned at one end of said receptacle with its

axis at an angle with said receptacle and arranged to engage the cake of soap on one side only of its axis of rotation.

8. In a device of the class described, a receptacle for a cake of soap, a spindle therein adapted to support the cake of soap and permit a rotary movement thereof on said spindle, a rotative cutter at one end of said spindle having its axis at an angle therewith and so arranged that the cutter will engage the cake of soap on one side only of said spindle thereby causing said cake of soap to rotate during the process of cutting.

9. In a device of the class described, a receptacle, a spindle therein, a sleeve positioned on said spindle adapted to support a cake of soap and to permit a rotary movement thereof about said spindle, and a rotative cutter at one end of said spindle arranged to operatively engage the cake of soap supported by said sleeve.

10. In a device of the class described, a receptacle, a spindle therein, a sleeve positioned on said spindle adapted to support a cake of soap and to permit a rotary movement thereof about said spindle, and a rotative cutter at one end of said spindle having its axis at an angle therewith and adapted to engage and progressively comminute the cake of soap supported by said sleeve and simultaneously to cause a rotary movement thereof.

Signed this 20th day of March, 1908, before two subscribing witnesses.
